United States Patent Office

Des. 198,030
Patented Apr. 21, 1964

198,030

CONTROL KNOB

Walter L. Hill, South Lincoln, and Henry B. Hoover,
Lincoln, Mass., assignors to Raytheon Company, Lexington,
Mass., a corporation of Delaware

Filed Apr. 26, 1963, Ser. No. 74,635

Term of patent 14 years

(Cl. D26—13)

FIG. 1

FIG. 2

FIG. 1 is a plan view of a control knob showing our new design; and

FIG. 2 is an elevation view.

The dominant features of our new design are shown in solid lines in the drawing.

We claim:

The ornamental design for a control knob, substantially as shown and described.
